UNITED STATES PATENT OFFICE.

ELZIRA HUBBARD, OF CARLINVILLE, ILLINOIS.

DESIGN FOR A GRAVE-VAULT.

SPECIFICATION forming part of Design No. 29,609, dated November 1, 1898.

Application filed October 6, 1898. Serial No. 692,857. Term of patent 7 years.

To all whom it may concern:

Be it known that I, ELZIRA HUBBARD, a citizen of the United States, residing at Carlinville, in the county of Macoupin and State of Illinois, have invented and produced a new and original Design for a Grave-Vault, of which the following is a specification, reference being had to the accompanying drawings, forming a part thereof, in which—

Figure 1 is a plan view of a grave-vault embodying the features of my design. Fig. 2 is a side elevation, and Fig. 3 is a section taken on the line 3 3 of Fig. 2.

In plan view the vault is ovoid in general contour, and in side elevation and cross-section the top A is arched. The body B presents convexed sides and end surfaces, and the convexity of the sides and ends is continued at the bottom of the vault. The bottom of the vault is interrupted by transverse

cavities b, and at the sides of the body and the top handholds b' appear. The body is decorated near the top with a continuous flange b², which flange is given a dished contour at the top, and a continuous cylindrical flange a is formed at the margin of the top, which in the cross-section of the vault appears to fit into the dished-body cavity b². 25

The leading feature of the design consists of an arched top, a body having convexed 30 sides and end and bottom surfaces, and flanges at the meeting of the top with the body, the flanges appearing to interlock.

I claim—

The design for a grave-vault herein shown 35 and described.

ELZIRA HUBBARD.
